ATTORNEY.

UNITED STATES PATENT OFFICE.

GEORGE F. MEYERS, OF NEW YORK, N. Y.

GAUGE FOR SHEET-CUTTING MACHINES.

Application filed April 17, 1926. Serial No. 102,608.

The invention relates to sheet cutting machines and has particular reference to the back gauge of such machines against which the sheets are positioned preliminary to being fed between the cutters.

In some forms of these cutting or shearing machines the gauge, in the form of a metal bar, is secured to the wooden bed of the machine by fastening screws engaging directly in the bed. In the use of the machine the operators bring the sheets against this gauge bar with some considerable force in positioning the same, particularly in those cases where the sheets are handled in bunches and it becomes necessary to strike them against the gauge bar with some force in order to bring the edges of the respective sheets of the bunch into registry with each other and in contact with the gauge. Such continuous striking of the sheets against the gauge has a tendency to loosen its holding screws in the wooden bed of the machine and this results in throwing the gauge out of adjustment and the consequent irregular or improper cutting of the sheets.

The continuous loosening of the screws in this way soon enlarges their openings in the wooden bed to such an extent that effective retightening of the same is prevented, whereupon it becomes necessary to either change the position of the gauge on the bed, which is undesirable, or else provide the gauge with new screw openings to permit of the fastening screws being entered into the bed at new points without change in position of the gauge, and this operation of forming new screw-openings is objectionable both on account of expense and also in that it disfigures the gauge.

Having the foregoing in mind, it has been the object of my present invention to provide an improved construction of gauge by means of which the objectionable features referred to may be avoided and accurate adjustment of the gauge be maintained. This object is effected by means of the novel features of construction hereinafter described and claimed and which are illustrated in the accompanying drawings, in which—

Fig. 1 is a plan view of so much of a cutting or shearing machine as is necessary for the proper illustration of my invention.

Fig. 2 is an enlarged cross section of the gauge in position on the machine bed, taken on the line 2—2 of Fig. 1.

Fig. 3 is an enlarged longitudinal section of the gauge in position on the machine bed, taken on the line 3—3 of Fig. 5.

Fig. 4 is a sectional plan with the section taken on the line 4—4 of Fig. 2.

Fig. 5 is an irregular section taken generally on the line 5—5 of Fig. 3.

Fig. 6 is an end view looking from the left in Fig. 5, with the end adjusting screw in section on the line 6—6 of said Fig. 5.

The cutting machine to which my invention is applied is or may be of usual construction and operation, the same comprising a bed *a* mounted upon a suitable frame (not shown); a cutting or shearing device consisting of a stationary cutter *b* and a cooperating movable cutter *c*; and a treadle operated vertically movable clamp *d* for holding the sheets stationary after being positioned and during the cutting operation.

The gauge embodying my present improvements is located at one side of the bed and extends in a direction at right angles to the cutters, whereby the sheets, after being positioned with one edge against said gauge, may be guided thereby between the cutters to have their leading edges cut square with those in contact with the gauge.

This gauge comprises a lower or base member 2 in the form of a relatively long bar, preferably of metal, which is adapted to be permanently fastened in position on the table, as means of wood screws 3, the heads of which are counter-sunk below the top surface of the bar as best shown in Fig. 3. Mounted upon this base member 2, for both transverse and longitudinal adjustments with respect thereto, is a second gauge member 4 which constitutes the gauge proper and with which the sheets directly engage. This second or adjustable gauge member is right angular in cross section, as best shown in Figs. 2 and 6, and is mounted on the base member 2 with one flange 4' resting upon the top surface of said base member for adjustable sliding movement thereon and with its second or vertical flange 4'' extending downwardly over the inner face side of the base member into contact with the surface of the bed or table *a*, this vertical flange providing the gauge face against which the sheets are positioned and guided.

This adjustable member 4 is held in ad-

justed position on the base member by means of fastening screws 6 which are tapped into the base member and which extend through enlarged openings 7 in the upper horizontal flange of the member 4 with their heads spanning said openings and engaging the top surface of the flange, as best shown in Figs. 2 and 3. With this arrangement, the adjustable member 4, upon the loosening of the screws 6, may be readily adjusted on the base member 2 to direct the sheets squarely through the cutter device, and then be secured in such adjustment by a retightening of said screws. As a further means for maintaining the member 4 in its adjusted position, a series of stop screws 8 are threaded through transversely arranged openings in the base member with their front ends projecting beyond the face side of the latter into engagement with the rear side of the vertical flange 4" of the member 4, as best shown in Figs. 2 and 4, and with their rear ends exposed at the rear side of said base member for engagement by a screw driver or like adjusting tool. By setting up these screws 8 against the flange 4" of the adjustable gauge member following the adjustment of the latter by the main adjusting screws 6, assures the positive locking of said gauge member in its adjusted position.

In the use of a single gauge member as heretofore, the loosening of its fastening screws as referred to permitted of a slight tilting of the same when struck by the sheets brought forcibly against the same, and this in turn permitted of the edge of the sheets getting beneath the gauge bar and so interfering with the proper gauging and feeding of the sheets. I avoid such objectionable feature in the present instance by forming the vertical flange 4" of the member 4 of a slightly greater depth than that of the base member 2 whereby its lower edge may be forced tightly against or into the top surface of the table by the adjusting screws 6, as shown in Fig. 2, and thus avoid liability of the edges of the sheets accidentally getting beneath the same.

Another feature of my invention has to do with the scale for determining desired sizes or dimensions into which the sheets are cut. For instance, in some of these cutting machines, scales are formed permanently on the table by means of which the sheet may be cut to certain desired sizes by setting the rear edges of the same back from the stationary cutter a certain distance as determined by the scale to give the desired size. With this arrangement of scale, it is set with the starting point or zero at the edge of the lower or stationary cutter. As an incident to the use of the machine, however, it becomes necessary to remove these cutters more or less frequently for sharpening and this

results in a narrowing of the cutter blades and the consequent inaccuracy of the scale by reason of the change in position of the zero point.

To provide for such change in position of the zero point of the scale resulting from sharpening of the cutter blade, I provide an adjustable scale member which may be shifted in position to compensate for any variation in the width or thickness of the cutter blade. This I accomplish by providing the adjustable gauge member 4 with scale markings, as at 10, and making provision for its longitudinal adjustment on the base member 2 in a direction toward and from the cutter. Such adjustment is obtained simply by making the screw openings 7 sufficiently large to permit of a longitudinal movement of the gauge member 4 on the base member as well as the transverse movement thereon hereinbefore referred to; and in order to obtain a fine and accurate adjustment of the member 4 in such direction I have formed the same with a downwardly hanging flange 12 at its rear end having a perforation 14 in which is mounted a screw 15 having its threaded end tapped into an opening in the rear end of the base member 2, as shown in Figs. 3 and 4. This screw 15 is secured in endwise connection with the flange 12 by means of collars 16—16 on the screw engaging the opposite faces of the flange as shown. In this way, the gauge member 4 may be shifted by the screw 15 to accurately adjust its scale with respect to the cutter and then be further held in adjusted position by retightening of the screws 6. The perforation 14 in the flange 12 to receive the screw 15 is made elongated in a direction transversely of the gauge (see Fig. 6) to permit of the adjustment of the gauge member in such direction as hereinbefore described.

What I claim is:

1. In a sheet cutting machine, the combination with the sheet supporting bed and the cutting device, of a sheet gauge comprising a base member mounted on said bed, a right angled member mounted on said base member with one flange thereof resting upon the upper surface of the base member and with the other or vertical flange bearing at its lower edge upon the sheet supporting bed, and means for securing said right angled member in adjusted position on the base member.

2. In a sheet cutting machine, the combination with the sheet supporting bed and the cutting device, of a sheet gauge comprising a base member mounted on said bed, a right angled member mounted on said base member with one flange thereof resting upon the upper surface of the base member and with the other or vertical flange bearing at its lower edge upon the sheet supporting bed, said vertical flange being of greater depth

than the base member, and means for securing said sheet engaging member in adjusted position on the base member and with the lower edge of its vertical flange pressed against the sheet supporting bed.

3. In a sheet cutting machine, the combination with the sheet supporting bed and the cutting device, of a sheet gauge comprising a base member mounted on the bed, a right angled member adjustably mounted on said base member with one flange thereof resting upon the upper surface of the base member and with the other or vertical flange overlying the base member at the gauge side thereof, and means for securing said adjustable gauge member in adjusted position on the base member including set screws threaded into the base member with their inner ends bearing against the inner side of the

said vertical flange of the adjustable gauge member.

4. In a sheet cutting machine, the combination with the sheet supporting bed and the cutting device, of a sheet gauge mounted on the bed in a position at right angles to the cutting device and comprising a fixed base member, a sheet engaging member adjustably mounted on said base member for movement in a direction toward and from the cutter and being provided with scale markings thereon, an adjusting screw connecting the sheet engaging member with the base member for adjusting the same on said base member relatively to the cutter and means for securing said sheet engaging member in adjusted position on the base member.

In testimony whereof I affix my signature.

GEORGE F. MEYERS.
